UNITED STATES PATENT OFFICE

GEORGE CHARLES LEWIS, OF NEW DORP, NEW YORK, ASSIGNOR TO COLUMBIAN CARBON COMPANY, OF NEW YORK, N. Y., A CORPORATION OF DELAWARE

MANUFACTURE OF CARBON BLACK

Application filed December 31, 1927. Serial No. 243,899.

As is well known, the burning of natural gas or other hydrocarbons with the flame impinging on a channel or other metal surface is employed commercially for the production of carbon black, but the yield is very small in comparison with the theoretical maximum of the carbon in chemical combination in the gas being burned. In spite of the low yield this method is still employed to a very large extent, because no known method produces a carbon black having exactly the same combination of characteristics such as fineness, softness, purity, color, dispersibility, etc., for which there is a large demand.

The main object of my invention is to secure an increased yield of carbon black from the hydrocarbon employed, and without changing to any appreciable or objectionable degree the highly desirable characteristics of the product which result from the impinging of the flame on the collecting surface.

I have discovered that the deposition of the carbon from a flame where there is incomplete combustion is affected by the frequency of the light waves playing upon the flame or depositing surface, and that an increase in the amount of short length light waves materially increases the separation and deposition of the incandescent carbon and an increase in the yield of carbon black obtained from the burning of a given amount of hydrocarbon. The luminosity of the flame is in part dependent upon the incandescent carbon in the flame, and the light rays emitted therefrom are very largely at the red or yellow low frequency end of the spectrum. Thus the light rays emitted from one flame include a very small and practically unmeasurable amount of the short length waves or ultra violet light rays at or beyond the opposite end of the visible spectrum.

I have discovered that by positioning a source of light adjacent to the flame or the depositing surface of such a character that it emits a comparatively large amount of the ultra violet or other short length light waves, a larger proportion of the carbon in

the material burned in the flame will separate out and collect on the depositing surface. Although the auxiliary source of light which I employ may include light rays of the entire spectrum, it is not essential that there be employed other than the high frequency rays. Although the rays which appear to have the most desirable effect are those within the range commonly referred to as "ultra violet", I desire to include in the term "short length" the rays at the violet end of the spectrum, the ultra violet rays, and those of shorter wave length than the ultra violet, such for instance as the Roentgen or X-ray. Light rays of a wave length greater than 302 mu have little or no effect, and by the term "short wave" I include only those light rays which have a wave length of 302 mu or less.

Any suitable apparatus may be employed for the production of the desired high frequency or short length light rays, but no apparatus is suitable for the purpose unless it has a substantial proportion of emitted rays below 302 mu. Merely as an example I may mention a mercury vapor lamp of the quartz tube type. This should be so mounted that the light rays may impinge on both the flame and on the depositing surface. It is known that a depositing surface of iron appears to have certain catalytic effect in securing a larger deposition of carbon black than can be obtained with certain other materials, and it is possible that the short length light waves in acting upon the metal surface of the depositing plate increase the catalytic action of the latter and thereby increase the deposition of carbon black. It is also possible that the increased deposition is due primarily to the action of the light rays on the incandescent carbon particles in the flame. It is probably due to a combination of these effects, but exact data on this point are difficult to obtain. The source of short length light waves should be so positioned that it does not become coated with any depositions of carbon which would interfere with the emission of the light rays and also so positioned that it is not objectionably affected by the high temperature existing in

the immediate vicinity of the flame. The said source may be so designed or so shielded that the ultra violet or other short wave length rays are directed only toward the 5 flame and the depositing surface, although this is not essential.

In the single figure of the accompanying drawing I have illustrated somewhat diagrammatically an apparatus for carrying 10 out my invention.

The drawing shows a pair of iron plates or channels 10 against which the flames 11 from burners 12 may play. These channels and their relationship to the burners may be 15 that commonly employed in the industry, and suitable means are used for effecting the movement of the channels back and forth through the flame with brushes or other means to scrap off the deposited carbon 20 black.

In carrying out my invention I employ a source of short wave length rays such as a tube 13. In order to get the maximum effect this is positioned between two adjacent 25 burners or rows of burners, and beneath the channels 10 so that the rays therefrom may play on or bombard the flames and the depositing surfaces upon opposite sides thereof. The tube 13 being below the burners is 30 somewhat away from the heat of the latter, and being below and between the channels does not become coated with any deposited carbon.

I find that by means of my invention I am 35 able to very materially increase the amount of carbon black which would otherwise be produced from a given hydrocarbon. The hydrocarbon may be natural gas, or it may be any other suitable material adapted for 40 burning to produce carbon black. Although the invention is primarily useful for increasing the production of carbon black, it also may be employed for increasing the yield of lamp black where no depositing 45 plates are employed. In each case the incomplete combustion of the hydrocarbon results in the production of free carbon, and the ultra violet rays increase the yield of the unburned or separated carbon which 50 may be collected as the desired product.

Having thus described my invention what I claim as new and desire to secure by Letters Patent is:

1. The method of producing carbonaceous 55 deposits from a flame, consisting in subjecting the flame to the action of light rays from a source of light emitting a substantial amount of light waves of shorter length than those forming the main portion of the 60 light from said flame.

2. The method of producing carbonaceous deposits such as carbon black or lamp black from a flame in which incomplete combustion is effected, said method consisting in 35 bombarding the flame with ultra violet rays.

3. The method of producing carbonaceous deposits which consists in effecting incomplete combustion in a flame and subjecting the flame to the action of a source of light emitting a substantial amount of light rays 70 of short wave length.

4. The method of producing carbonaceous deposits which consists in effecting incomplete combustion in a flame and subjecting the flame to ultra violet rays. 75

5. The method of producing carbon black which consists in cooling a flame to effect a deposition on the cooling medium and delivering light rays of short wave length to the flame. 80

6. The method of producing carbon black which consists in cooling a flame to effect a deposition on the cooling medium and delivering light rays having a wave length below 302 mu to the surface of the cooling 85 medium.

7. The method of producing carbon black which consists in cooling a flame to effect a deposition on the cooling medium and delivering ultra violet rays to the flame. 90

8. The method of producing carbon black which consists in cooling a flame to effect a deposition on the cooling medium and delivering ultra violet rays to the surface of the cooling medium. 95

9. The method of producing carbonaceous deposits which consists in playing a flame and light rays of short wave length on a metal surface at the same point.

10. The method of producing carbonaceous deposits which consists in playing a flame and light rays of short wave length on a metal surface at the same point, and continuously moving the surface to bring fresh parts thereof into action. 100

11. The method of increasing the yield of carbon black produced by the action of a gas flame on a moving iron surface, which includes the step of bombarding the iron surface with ultra violet light. 105

12. The method of increasing the yield of carbon black produced by the action of a gas flame on a moving flame, which includes the step of bombarding the flame with ultra violet light. 110

13. The method of increasing the yield of carbon black produced by the action of a gas flame on a moving iron surface, which includes the step of bombarding the iron surface and flame with ultra violet light. 115

14. An apparatus for producing carbon black including a burner and a source of ultra violet rays disposed adjacent thereto.

15. An apparatus for producing carbon black including a depositing surface, a burner so positioned that the flame therefrom plays on said surface, and means for delivering light rays of short wave length to said flame. 125

16. An apparatus for producing carbon 130

black including a depositing surface, a burner so positioned that the flame therefrom plays on said surface, and means for delivering light rays of short wave length to said

5 surface.

17. An apparatus for producing carbon black including a depositing surface, a burner so positioned that the flame therefrom plays on said surface, and means for delivering

10 ultra violet rays to said flame.

18. An apparatus for producing carbon black including a depositing surface, a burner so positioned that the flame therefrom plays on said surface, and means for delivering

15 ultra violet rays to said surface.

Signed at New York in the county of New York and State of New York this 21st day of December A. D. 1927.
